UNITED STATES PATENT OFFICE

HARRY LEE, OF LIVINGSTON, MONTANA

MOBILE KITCHEN CHAIR

Application filed April 10, 1930. Serial No. 443,135.

This invention relates to a kitchen chair and it aims to provide a construction which may be propelled about the kitchen by an operator, to enable an operator, particularly the housewife, to perform all duties while seated so that she will not have to stand incidental thereto and become as weary as under present conditions.

Another object is to provide a novel construction wherein the device may be propelled either by hand or by foot.

A further object is to provide a novel construction wherein a table may be carried by the device and adjusted to different heights in order to facilitate inspection of articles from a stove, at the same level at which they are removed from the stove.

A further object is to provide a novel means for steering the device which may be operated by the said table or other means as preferred.

Various additional objects and advantages will become apparent from a consideration of the description following taken in connection with accompanying drawings illustrating an operative embodiment.

In said drawings:—

Figure 1 is a view of the invention in side elevation,

Figure 2 is a view in rear elevation,

Figure 3 is a central longitudinal sectional view, and

Figure 4 is a front elevation.

Referring specifically to the drawings, 10 designates the body or platform having frame members 11 longitudinally arranged and fastened to the under surface thereof, which members depend vertically at 12 at the rear and journal a driving shaft 13 which has 15 wheels 14, keyed thereto and also pinions keyed thereto adjacent the wheels 14. A connecting bar or brace is provided at 16.

A seat or chair 17 for the housewife is supported by a spring bar 18 which extends 20 through the platform 10 and at its lower end terminates in a journal or bearing 19 for the said shaft 13, the bar 18 being secured in any suitable manner as at 20 to the cross member 16.

At the front, wheels 21 are journaled on

an axle 22 carried by a fifth wheel 23 from which a vertical post 24 rises, being swivelled in a plate 25 supported and carried by L-shaped portions 26 forming the forward terminals of the frame members 11. Such 55 portions 26 are braced by a bar 27 which is suitably fastened thereto and provided with a bearing 28 constituting a journal for the post 24.

The post 24 is adapted to be operated in 60 order to turn the axle 22 to steer the device. To this end the upper portion thereof is hollow and has a rod 29 slidably disposed therein maintained in uppermost position by an expansive spring 30. Said rod 29 has a pin 65 31 therein which engages in an elongated slot 32 in the post. Said rod 29 at the top carries a table 33. In lieu of the table 33 and rod 29, an ordinary steering handle or connection 70 may be provided.

The drive shaft 13 is provided with two cranks 34 arranged at right angles to each other to which pitman 35 is pivoted which is also pivoted at 36 to pedal levers 37 pivoted as at 38 to a rod 39 fastened to the frame portions 11. Foot engaging elements of the pedals 37 are shown at 40 and are accessible to the operator or housewife using the seat 17.

In addition to the device being operable by the feet through the medium of the pedal levers 37 and connected parts, the device may selectively be propelled through the operation of hand levers 41 which are pivoted on a shaft 42 mounted by the frame members 11. Such levers 41 are pivoted at 43 to pitmen 44 eccentrically pivoted at 45 to gear wheels 46 which are arranged in mesh with the pinions or gear wheels 15. Said gear wheels 46 are keyed to a shaft 47 journaled in bearings or hangers 48 depending from the frame members 11.

As a result of the construction described, the housewife may be seated in the chair 17 while performing her chores about the kitchen and house and may operate the same by the levers 41 or pedals 37, according to her desire or whenever members of the body are free for use in propelling the device. In addition, the device may be readily steered 100

through the turning of the post 24. The table 33 enables articles to be accommodated or deposited thereon to be carried from place to place and particularly enables articles that are hot or difficult to handle to be accommodated directly from a stove or support and the fact that the same is vertically movable, enables adjustment thereof to the same height at which the article on the stove or the like is removed from the stove.

The particular shape of the spring 18 guards against the device tipping backward when the weight of the operator is thrown forward.

15 The wheels 14 and 21 are each equipped preferably with rubber tires in any suitable manner as at 49.

Various changes may be resorted to provided they fall within the spirit and scope of 20 the invention.

I claim as my invention:—

1. A device of the class described comprising a body, a crank shaft journaled on the under side thereof, wheels on said crank 25 shaft, pinions carried by the crank shaft, gear wheels in mesh with said pinions, a shaft on which the gear wheels are carried, means journaling the latter shaft from the body, pitmen on the outer side of and connected to 30 the gear wheels, manually operable levers pivoted to the body and to the pitmen, pitmen inwardly of the gear wheels connected to the cranks, and pedals pivoted to the body and to the latter pitmen forwardly of said levers.

35 2. A device of the class described comprising a body, a crank shaft journaled on the under side thereof, wheels on said crank shaft, pinions carried by the crank shaft, gear 40 wheels in mesh with said pinions, a shaft on which the gear wheels are carried, means journaling the latter shaft from the body, pitmen on the outer side of and connected to the gear wheels, manually operable levers 45 pivoted to the body and to the pitmen, pitmen inwardly of the gear wheels connected to the said cranks, pedals pivoted to the body and to the latter pitmen forwardly of said levers, a chair, a supporting bar securing the 50 chair to the body, said bar extending below the body and having a bearing for said driving shaft.

In testimony whereof I affix my signature.
HARRY LEE.
